POST PULLING APPARATUS

Willard Harding Osmundson,
Sturgeon Bay, Wis.

Application October 27, 1948, Serial No. 56,888

8 Claims. (Cl. 254—30)

1

This invention relates to a device for pulling posts or like objects from the ground in which they are held fast or moored. In particular, the invention relates to a post pulling attachment which is adapted to be secured to the hydraulic lift mechanism of a tractor.

One of the objects of this invention is to provide a post pulling attachment which is simple in construction, ruggedly formed and positive in operation and which can be attached to the lifting means with which it is employed with minimal difficulty and without requiring modification of the structure of tractor draw links in order to utilize the draw link assembly of a tractor as the lifting means.

Another object is to provide a post pulling device which is adapted to effectively grip for removal posts of widely variant diameters without necessitating adjustment of the gripping means and which when employed in conjunction with tractor draw links permits adjustments which may be desirable to be made by the operator from his normal operating station.

An important feature of the present invention resides in providing a post pulling attachment which does not cause deformation or weakening of the posts which are removed by use of the attachment and thereby enables reuse of many posts which otherwise could not be salvaged.

The invention further provides a gripping element which is not dependent on coacting jaws having serrated or other sharpened biting edges which are subject to dulling for an effective working grip on the post to be pulled.

Other objects and advantages of the invention will be apparent from the following detailed description when taken in connection with the accompanying drawings in which:

Figure 1 is a plan view of the post pulling attachment illustrating its general shape and the arrangement of the working parts on the frame.

Figure 2 is a front view of the attachment illustrating the normal position of the gripping arms and in dotted lines the position of the gripping arms in relation to the frame when the post to be pulled is positioned in the gripping element.

Figure 3 is a side view showing the attachment assembled on tractor draw links in their lowered position and a post within the gripping element, and in dotted lines the same assembly in raised position, and

Figure 4 is a diagrammatic view of the post puller.

In general, the post pulling attachment com-

2

prises a frame which is adapted for attachment to a lifting means, a pair of gripping arms pivotally mounted on the frame and a length of chain which is fixed to the arms in a manner which forms a grip for the post to be pulled.

In the embodiment of the invention illustrated in the accompanying drawings 10 indicates a frame of generally U-shaped configuration. The frame is braced against distortion by the ribs 11 regularly spaced along the length of the frame.

The extensions or legs 12 of the frame are slightly divergent and formed to lie in generally parallel relationship with the draw links 13 of a tractor on which the attachment is assembled. 15 The terminal ends of the extensions 12 are provided with openings 14 through which pins 15 extend. The pins 15 also extend through corresponding openings 16 provided in the draw links 13 at the ends thereof. The removable attachment means thus provided retain the ends of the extensions 12 of the frame in fixed relationship with the draw links.

Retaining lugs 17 are formed integrally, or otherwise rigidly affixed, to the frame forwardly 25 of the pivoted mountings of the extensions 12 and rest on the upper face of the draw links 13. The frame 10 is thus suspended in the plane defined between the draw links 13 from the support points provided by the pins 15 and the lugs 17.

30 Lift rods 18 are pivotally fixed to the draw links 13 at 19. The lift rods are connected at their other ends to the linkage actuated by the hydraulic lift mechanism of a tractor (not illustrated), the operation of which causes the raising or lowering of the draw links 13 and therewith the associated post puller assembly. Such draw links are employed in tractors utilizing the method of implement attachment and control commonly known as the "Ferguson system."

35 40 The attachment may be equally well used in connection with pivoted lifting links and lift mechanism of the type shown in U. S. Patent No. 2,436,510 to Ferguson, dated February 24, 1948.

Pivot plates 20 are rigidly affixed to the horizontal flanges of the longitudinal extensions 12 in any suitable manner. The pivot plates are provided with bracket plates 21 in which suitable journals for the shafts 22 are provided. The gripping arms 23 are pivoted on the shafts 22 for axial movement on the said shafts.

The attachment is provided with a gripping element comprising the gripping arms 23 and the chain 24.

The gripping arms 23 are provided with the slots 25 in their terminal ends which are adapted

to receive a link of the chain 24. The chain is inserted in the slots in a manner which will result in a bight of chain being formed between the upwardly extending gripping arms when the arms are in their normally disengaged position.

The gripping arms are normally held in an upwardly extending position by the action of the springs 26, which are secured at one end to the clevises 27 fixed to the vertical strengthening webs of the arms 23 and at the other end to the plates 20. It has been found that use of a spring tension which results in spacing the terminal ends of the chain supporting gripping arms a distance of approximately 3½ inches adapts the attachments for removal of posts varying in diameter in the degree normally encountered without further adjustment. A stop 28 is interposed between the arms 23 and the plate 20 and limits the movement of the arms 23 in upwardly direction about the shafts 22 under the force of the springs 26.

It is apparent from the foregoing description that when the attachment as described is assembled on the draw links of a tractor that the tractor may be backed into position which will allow the post to be received within the open end of the frame between the longitudinal extensions 12. The face of the post first contacting the attachment will cause the gripping arms to rotate upwardly about the shafts in the event that the diameter of the post is greater than the space normally maintained by spring action between the terminal ends of the gripping arms. At this point the forward face of the post will also contact the bight of chain suspended between the gripping arms. Further rearward movement of the tractor will swing the bight of chain backwardly and thus cause it to move upwardly on the post. When the tension on the chain has increased to the point which permits no further upward movement of the chain on the forward face of the post a tendency to rotate downwardly about the shafts 22 will be imparted to the gripping arms 23. The catenary defined by the bight of chain is such that this downward tendency will not be imparted to the gripping arms until the diameter of the post has passed within terminal ends of the gripping arms. With the post thus positioned in the grip, as illustrated in solid lines in Figure 3, the hydraulic lifting means is actuated resulting in upward movement of the draw links and the attachment assembled therewith into the position indicated in dotted lines in Figure 3. The upward movement of the attachment will result in the gripping arms rotating downwardly about their axis of rotation, as from the solid line to the dotted line position shown in Figure 2, thereby tending to force the post rearwardly into the bight of chain as the gripping arms move downwardly along the rearward curvature of the post. The chain is thus tensioned to the degree necessary to retain the post at the gripped point and further upwardly movement of the attachment will dislodge the post.

It is apparent that the construction of the gripping element permits ready adjustment for pulling posts of diameters larger or smaller than those to which the gripping element automatically adjusts by positioning the gripping element directly behind and below the normal tractor operating station. The adjustment consists merely of removing the particular link of chain held in the slotted end of a gripping arm and

re-inserting a link which will result in the desired catenary.

It is notable that when a post is removed in the manner described, the force necessary to dislodge the post is not applied at localized points but is applied generally throughout the circumference of the post. Deformation of the posts removed is thus minimized and many more posts may be salvaged for re-use than was heretofore possible.

When the post has been dislodged and removed the draw links are hydraulically lowered and the consequent downward movement of the attachment will cause the gripping arms to rotate upwardly about their axis and automatically release the posts from the gripping element.

It is to be understood that although the invention was herein described with reference to a single embodiment thereof, that changes and modifications may be made without departing from the scope of the invention as defined in the following claims.

Having thus described the invention, what is claimed as new and desired to be secured by Letters Patent is:

1. In combination with a lifting means, a post puller comprising a frame secured to said lifting means, two oppositely disposed upwardly extending gripping arms, said arms provided with slots in their terminal ends and pivotally mounted to said frame, and a length of chain adapted to be received in said slots.
2. In combination with a lifting means, a post puller comprising a frame secured to said lifting means, a plurality of upwardly extending gripping arms, said arms pivotally mounted on said frame, and a length of chain fixed to the ends of said arms.
3. In combination with hydraulically operated tractor draw links, a post puller comprising a frame secured to said draw links, two oppositely disposed upwardly extending gripping arms, said arms provided with slots in their terminal ends and pivotally mounted on said frame, and a length of chain adapted to be removably fixed in said slots.
4. In combination with hydraulically operated tractor draw links, a post puller comprising a frame pivotally mounted on the ends of said draw links, retaining lugs on said frame adapted to rest on said draw links, two oppositely disposed upwardly extending gripping arms, said arms provided with slots in their terminal ends and pivotally mounted on said frame, and a length of chain adapted to be received in said slots.
5. A post puller as described in claim 4 comprising two springs, said springs secured at one end to an intermediate section of said arms and at the other end to said frame thereby retaining said arms in their upwardly extending position.
6. A post pulling device comprising a frame, gripping arms pivotally mounted on opposite sides of said frame, fastening lugs fixed to either side of said frame arranged to operatively engage lifting means disposed beneath said frame, and a gripping chain fixed to the ends of said arms, said chain having a bight intermediate the said ends of said arms sufficient to permit the diameter of a post to be pulled to pass between the arms as the post to be pulled, passing along the longitudinal axis of the frame from the open end thereof toward said chain, moves into engagement with the said chain and causes said arms to be drawn downwardly.

7. A post pulling device comprising a U-shaped frame, oppositely disposed gripping arms pivotally mounted on the respective longitudinally disposed sides of said frame, resilient means connected with intermediate portions of said arms, respectively, and with said frame to yieldingly support said arms in an upwardly extending direction, said arms being provided with slots in their terminal ends, a length of chain adapted to be received in said slots, said chain having a bight intermediate the said ends of said arms sufficient to permit the diameter of a post to be pulled to pass between the arms as the post to be pulled, passing along the longitudinal axis of the frame from the open end thereof toward said chain, moves into engagement with the said chain and causes said arms to be drawn downwardly.

8. In combination with hydraulically operated tractor draw links, a post puller comprising a frame pivotally mounted on the ends of said draw links, retaining lugs on said frame adapted to rest on said draw links, two oppositely dis-

posed upwardly extending gripping arms, said arms provided with slots in their terminal ends and pivotally mounted on said frame, and a length of chain adapted to be received in said slots, said chain having a bight intermediate the said ends of said arms sufficient to permit the diameter of a post to be pulled to pass between the arms as the post to be pulled, passing along the longitudinal axis of the frame from the open end thereof toward said chain, moves into engagement with the said chain and causes said arms to be drawn downwardly.

WILLARD HARDING OSMUNDSON.
